UNITED STATES PATENT OFFICE.

EDWARD P. ARMSTRONG, OF PORTLAND, OREGON.

GANG SAW.

Application filed May 6, 1926. Serial No. 107,138.

My invention relates to that type of gang-saw commonly used in saw mills, which comprises a reciprocated sash carrying a plurality of spaced saws.

5 The weight of this sash, together with its saws, is considerable, weighing approximately three tons, and the saw-sash is reciprocated at a relatively high speed, approximately 250 strokes per minute. Hence, 10 this great mass, and the relatively great lineal speed at which it is reciprocated, tends to impose a great strain on the driving mechanism of the gang-saw. This driving mechanism commonly comprises a pitman connected to a crank-pin, and while these parts might be made of sufficient size to safely withstand said stresses, even then there would be great difficulty encountered in designing boxings which would stand up under 15 said conditions. Besides, the pounding incidental to the reciprocation of said mass tends to loosen the foundations.

The object of my invention is to provide means connected to said saw-sash by which 20 the shocks due to the great mass and momentum shall be substantially absorbed, and all undue stress on the crank-pin of the gang eliminated.

I attain my object by connecting the said 25 saw-sash to compression cylinders, and since a common construction of said gang-saw includes adjustable guideways, and guide-heads, operating therein, to which one end of said saw-sash is connected, one specific 30 mode of carrying my invention into practice is to provide said guideways with frame extensions and mounting compression cylinders on said extensions; the compression cylinders having pistons, which are connected 35 to and axially aligned with the path of motion of the guide-heads. In that way the guideways are arranged to suit all requirements of the gang saws without throwing the pistons and their connection with the saw-sash out of alinement. Furthermore, the opposite ends of the compression cylinders are each provided with a valve controlled fluid inlet; and a fluid passage connects said ends, 40 said fluid passage being provided with a valve.

A further incidental object of my invention is to provide two cushioning cylinders for the sash and saws carried thereby, said cushioning cylinders being arranged so as 45 to lie in a plane with the top slides for said sash and being connected by a relatively stiff

member adapted to sustain a substantial amount of compression or tension. Supporting devices are provided exteriorly of said guides and support said cylinders, said 60 supporting devices being carried by the frame of the machine. Said cylinders are connected by relatively stiff members adapted to sustain a high degree of compression and tension, thus providing mutual supports 65 for said cylinders to prevent their collapsing inwardly or yielding outwardly, that is, towards each other or from each other.

Further details of construction and mode of operation of my invention are hereinafter 70 described with reference to the accompanying drawings, in which:

Fig. 1 is a fragmentary elevation of a gang-saw embodying my invention, portions of the devices being shown as broken away 75 to disclose structural details;

Fig. 2 is a fragmentary elevation of a portion of said device on a larger scale, the parts being foreshortened; said figure disclosing details of the supports for said sashes 80 and the connections with said cushioning elements;

Fig. 3 is a longitudinal vertical section taken on the line 3—3 of Fig. 1, and in addition shows a cant or timber passing 85 through said saws;

Fig. 4 is a larger scaled foreshortened section taken substantially on the line 4—4 of Fig. 1;

Fig. 5 is a vertical section taken through 90 a gang-saw cushioned by a cylinder mounted below said saw, which arrangement is a modification of my invention;

Fig. 6 is a further vertical section disclosing a further modification of my invention 95 in which the cushion cylinder is connected to the saw frame through a rocker arm;

Fig. 7 is a horizontal section taken on the line 7—7 of Fig. 5; and

Fig. 8 is a horizontal section taken on the 100 line 8—8 of Fig. 6.

The gang saw embodying my invention comprises a frame *a* which is mounted upon a concrete foundation *b*. Intermediate supporting members *b'* are interposed between 105 the concrete foundation and the base *a'* of the frame, said auxiliary supporting members are preferably made of wood so as to have a slight amount of resiliency and thus eliminate a portion of the jar given to the 110 foundation. Holding-down bolts *b*² are provided, said bolts passing through the base *a'*

of the frame, the auxiliary supports b' and into the concrete foundation b .

Two crank shaft boxes c are provided for the crank shaft d ; upon said crank shaft a driving pulley, e , is fastened and a fly wheel e' is also commonly provided, for the usual purpose. Said crank shaft also carries a crank disc d' and a crank pin d^2 ; said shaft, disc, and pin usually being made of an integral forging to secure the maximum amount of strength.

Slidably mounted between the sides of said frame a is a saw-carrying sash f which is substantially rectangular and carries a plurality of spaced saws g . A wrist pin f' is usually formed as an integral portion of said sash and a pitman h connects said wrist pin f' and the crank pin d^2 , as shown in Fig. 1. Said sash carries guide pins $i-i$ at the lower end and $i'-i'$ at its upper end which are journaled in guide boxes i^2-i^2 and i^3-i^3 respectively which are slidably carried in the top and bottom slides j and j' respectively. Said bottom slides j' are pivotally carried by the sides of frame a upon pivots k and the top slides are carried by pivots k' . Each bottom slide is permitted free pivotal movement about its pivot k , while each top slide k' is held in adjusted position by set screws l which pass through slotted holes j^2 in the slide and are secured in the frame, thus permitting a degree of angular adjustment for the said top slides. The usual mechanism is provided for oscillating the bottom slides j' , said mechanism comprising the rock shaft m , which is connected to the crank shaft d , by an auxiliary pitman m' , which connects the auxiliary crank pin d^3 thereon with the crank arm m^2 on the rock shaft m . Said rock shaft also carries other crank arms m^3 which are connected with the lower slide j' , through longitudinally adjustable rods m^4 provided with a turn-buckle m^5 provided for making this adjustment. The rotary oscillation of said rock shaft m causes the corresponding motion of said arms m^3 which results in the oscillation of said lower slides j' about their pivots. The supports for the said pressure cylinders n are the top slides j upon each frame side, and the length of the slides is increased so that they extend above the top of the frame a , as shown clearly in Fig. 4. Pistons o reciprocate within the bore of each of said cylinders n , and are connected to the pins i' of the sash f by piston rods p . A by-pass q is provided in each of said cylinders which opens into the cylinder at its opposite ends; and a manually operable valve r is provided in each of said by-passes for controlling the flow of fluid therethrough. One of said valves is operated by the bell-crank lever r' and the other by the levers 4 . A link r^3 connects the bell-crank lever r' with the lever r^4 , and these bell-

crank levers are operated by a handle r^2 , so that the said valves may be opened or closed simultaneously. Said by-passes q and the manually operated valve r is provided to permit the operating devices to be started up without being required to compress the cushioning fluid contained in said cylinders, said fluid content usually being air.

When the gang-saw is started up, said valve r is opened, and thus the fluid is permitted to flow through said by-pass around said piston. After the machine has attained sufficient speed, said valve r is closed and the pistons of the cylinders n tend to support the sash independently of the pitman h .

The elimination of said cushioning devices at starting speed do not permit the frame to be vibrated by the reciprocating sash, because its speed is so low that the pounding is not severe. The bell crank r and the operating lever r^2 are arranged so as to hold the valve closed and said valves are only opened when said lever r^2 is lifted upwardly by the operator. Loss of fluid pressure in said cylinder through the packing s for the piston rod p or otherwise is compensated for through the vents t and t' in each of said cylinders, said vents being controlled by check valves u and u' , which are arranged to permit fluid to enter said cylinders but to prevent its return flow therefrom.

Said cylinders n are connected by an X-shaped compression member v which is stiff and adapted to sustain a relatively large amount of compression. Said top slides are supported exteriorly by the frame sides a , as shown in Fig. 1 and thus by bracing said slides and said cylinders against each other, said cylinders are prevented from collapsing towards each other by the stresses imposed thereon due to the reciprocation of the shaft and the saw carried thereby.

As shown in Fig. 3 feeding rolls w are provided for the cant or timber x to be cut, said rolls operating continuously. Additional top press rollers are usually provided for holding said cant or timber to said bottom rollers to prevent slippage; said top rollers form no part of my invention, however, and thus are not shown because they would otherwise cover structural features of the gang-saw with which my invention is not concerned.

As is apparent the weight of the reciprocating mechanism is supported between two opposed volumes of compressible fluid and thus the hammering caused by the forcing upwardly and downwardly of said sash and the saws carried thereby will be minimized and substantially eliminated by said cushionings. By arranging said cylinders upon said top slides they are always in alignment with said slides to prevent the binding or pinching of said piston rods p for the pistons, in said cushion cylinders, and the load

which they are called upon to support thus exerts its stresses substantially longitudinally of said rods so that said rods are subjected merely to tension and compression 5 and to little or no flexure. The top slides are also thus required to withstand straight tension and compression stresses, and little or no flexure or combination stresses and thus the machine is admirably adapted to 10 withstand and support the unusual stresses which machines of this character are subjected to.

In the modifications in my invention shown in Figs. 5 and 6 all of the details of 15 the gang-saws are the same as those in the previous figures and thus I will refer to the same by the reference characters given to the similar parts in said previous figures.

In Fig. 5 the cushion cylinder n^2 is connected to the crank pin d^2 on the crank disc d' by an auxiliary connecting rod 2, one end of said rod being connected to the end of the connecting rod h' and its other end being connected to a sliding block 3. Said latter 25 block is slidably mounted between opposed guiding flanges 4 carried by the frame a' of the machine. The piston rod p^2 for said cylinder n^2 is connected to said block which block thus serves as a cross-head.

In Fig. 6 the piston rod p^3 for the cylinder n^3 is connected to the rocker arm 5 through a sliding block 6 and to pivoted auxiliary connecting rod 7. Said sliding block 6 is 30 slidably engaged by guiding flanges 8 as shown in Fig. 8. Said rocker arm 5 pivotally mounted at its middle upon a bracket 9 carried by the frame a^2 and the opposite end of said rocker arm 5 is connected to the 35 guide box i^3 by a rod 10, as shown in Fig. 6. 40 The cylinders n^2 and n^3 in said modifications are exactly the same as shown in previous drawings and serve in a similar manner in resisting the pulsating blows caused by the reciprocation of the enormously heavy 45 saw sash.

I claim:

1. In a gang-saw having a reciprocating saw-sash, an adjustable guideway at each side of said saw-sash, a guide-head operating in each guideway to which guide-heads one end of said saw-sash is connected, each guideway having a frame extension, a compression-cylinder mounted on each of said frame extensions and a piston in each compression-cylinder, the piston being connected to and axially-aligned with the path of motion of its related guide-head, each compression-cylinder being provided with a valve controlled fluid-inlet at both ends, a 55 fluid passage connecting said ends, and a valve in said passage, means for operating the latter valves in unison.

2. In a gang-saw having a reciprocating saw-sash, an adjustable guideway at each 60 side of said saw-sash, and a guide-head op-

erating in each guideway to which guide-heads one end of said saw-sash is connected, each guideway having a frame extension, a compression-cylinder mounted on each of said frame extensions and a piston in each compression-cylinder, the piston being connected to, and axially-aligned with the path of motion of its related guide-head, and each compression-cylinder being provided with a valve-controlled fluid-inlet at both ends, a 70 fluid passage connecting said ends, and a valve in said passage, and means for operating the latter valves in unison, and each of said compression-cylinders being arranged to overhang the center line of motion of the 75 guide-head with which its piston is connected, and a rigid brace connecting said cylinders.

3. In a gang-saw comprising a frame and a reciprocating saw-sash, a guide-way adjustably mounted on said frame, a guide-head operating in said guide-way to which one end of said saw-sash is connected, a compression cylinder carried by said guide-way, a piston in said compression cylinder, and a 80 rod connecting said piston with said guide-head, said guide-way being adapted to permit limited angular adjustment thereof with respect to the line of motion of said saw-sash, and whereby said saw sash in reciprocating 85 will be given an oscillatory movement without creating lateral and flexure stresses.

4. In a gang-saw comprising a frame and a reciprocating saw-sash, a guide-way pivoted on said frame, a guide-head operating in said guide-way to which one end of said saw-sash is connected, a compression cylinder carried by said guide-way, a piston in 90 said compression cylinder, and a rod connecting said piston with said guide-head, said guide-way being adapted to permit limited angular adjustment thereof with respect to the line of motion of said saw-sash, and whereby said saw-sash in reciprocating 95 will be given an oscillatory movement without creating lateral and flexure stresses.

5. In a gang-saw comprising a frame and a reciprocating saw-sash, guide-ways adjustably mounted at each side of said saw-sash 100 on said frame, guide-heads operating in said guide-ways to which one end of said saw-sash is connected, compression cylinders carried by said guide-ways, pistons in said compression cylinders, rods connecting said pistons with said guide-ways, and a rigid brace connecting said cylinders, said guide-ways being adapted to permit limited angular adjustment thereof with respect to the line of motion of said saw-sash, whereby said saw-sash in reciprocating 105 will be given an oscillatory movement without creating lateral and flexure stresses.
